J. A. WRIGHT

GLARE SCREEN

Filed Jan. 17, 1923

UNITED STATES PATENT OFFICE.

JOHN A. WRIGHT, OF MAQUOKETA, IOWA.

GLARE SCREEN.

Application filed January 17, 1923. Serial No. 613,202.

To all whom it may concern:

Be it known that I, JOHN A. WRIGHT, citizen of the United States, residing at Maquoketa, in the county of Jackson and 5 State of Iowa, have invented certain new and useful Improvements in Glare Screens, of which the following is a specification.

This invention relates to an improved glare screen for motor vehicles and seeks, 10 as one of its principal objects, to provide a device which may be readily attached to a vehicle wind shield for cutting off the glare of the headlights of an oncoming vehicle or screening the eyes of the driver 15 against the rays of the sun.

The invention has a further object to provide a device which may be readily adjusted at any desired angle with respect to the wind shield or may be swung upwardly to a 20 position out of the way.

And the invention has as a still further object to provide a device which will be characterized by extreme structural simplicity but which, in practical use, will prove 25 entirely efficient.

Other and incidental objects will appear hereinafter.

In the drawings:

Figure 1 is a front elevation of my im- 30 proved glare screen,

Figure 2 is a vertical sectional view on the line 2-2 of Figure 1, looking in the direction of the arrows and showing the device applied, and

Figure 3 is a detail sectional view on the line 3-3 of Figure 1.

In carrying the invention into effect, I employ a supporting hanger which is preferably struck from a piece of suitable resil- 40 ient sheet metal and includes an oblong hinge bar 10 formed at its upper edge with bowed upstanding spring clamps 11 located near the ends of the bar while at its lower edge the bar is provided with a pair of hinge 45 loops 12 located near the ends of the bar and a third similar hinge loop 13 disposed substantially midway between said first mentioned loops. Swingly supported by the bar 10 is a screen frame comprising an 50 upper side rail 14 and end rails 15 integral with the side rail, the frame being open at its lower side since the presence of a lower side rail upon the frame would likely form an obstruction in the view of the driver.

As shown in Figure 3, the frame is chan- 55 neled to accommodate a screen of green

colored celluloid 16 or the like and formed on the end rails of the frame at their upper ends are hinge loops 17 straddling the loops 12 of the hinge bar 10. The rail 14 of the 60 frame is also provided with a hinge loop 18 mating with the hinge loop 13 of said bar and extending through the several loops is a hinge rod 19. At one end this rod is pro- 65 vided with a head 20 abutting the adjacent loop 17 of the screen frame as well as the adjacent end edge of the hinge bar 10 and freely surrounding the opposite end portion of the rod is a washer 21 abutting the other end edge of the bar as well as the other of 70 the hinge loops 17 of the frame. Threaded upon the latter end of the rod is a thumb nut 22 and surrounding the rod to bear be- 75 tween said nut and the washer is a spring 23.

In Figure 2 of the drawings, I have shown the device applied to a conventional vehicle wind shield 24. As will be observed, the clamps 11 are engaged over the top rail of the wind shield for supporting the device 80 to extend in front of the wind shield at the inner side thereof. The clamps will, of course, grip said rail so that the device will be firmly held in place without rattling and by providing the body bar 10, the 85 clamps will be braced by said bar with respect to each other so that individual canting of the clamps will be prevented. Furthermore, the bar will provide a rigid sup- 90 porting element for the screen frame sus- taining the frame at its ends as well as medially thereof. As will be appreciated, the device may be readily arranged at the proper point upon the wind shield so as to be in front of the driver, when the screen 95 16 will serve to shield the eyes of the driver against the glare of the headlights of an oncoming vehicle or other disagreeable light glare, and by swinging the screen upwardly, as shown in dotted lines in Figure 2, the 100 screen may be adjusted to the desired angle with respect to the wind shield or may be elevated to a position out of the way. When the screen is thus adjusted, the spring 23 will function to bind the screen in adjusted 105 position, the head 20 of the hinge rod and the washer 21 being held in tight contact with the lugs 17 of the screen frame for frictionally holding the frame against down- 110 ward movement. Furthermore, said head and the washer will cooperate with the end edges of the hinge bar 10 for holding the

hinge rod 19 against turning movement with the frame. I accordingly provide a particularly simple and efficient device for the purpose set forth and, as will now be 5 appreciated, a device adapted for a wide range of use.

Having thus described the invention, what is claimed as new is:

In a device of the character described, the 10 combination of a screen comprising a frame provided at its ends with a pair of upstanding hinge lugs, a unitary hanger comprising an oblong bar provided at its upper edge with spaced suspension clamps and at its 15 lower edge with a pair of depending hinge

lugs fitting between and mating with the lugs of the frame whereby the bar is limited against endwise movement relative to the frame, the end edges of the bar and frame lying flush with each other, a hinge rod 20 extending through said lugs swingingly connecting the frame with the bar and provided at one end with a head to contact corresponding end edges of the bar and frame, and spring pressed means upon the opposite 25 end of the rod to contact the opposite corresponding end edges of the frame and bar.

In testimony whereof I affix my signature.

JOHN A. WRIGHT. [L. S.]
